UNITED STATES PATENT OFFICE.

FRANKLIN YOUNG, OF PALMER, MASSACHUSETTS, ASSIGNOR TO THE
PALMER WIRE COMPANY, OF SAME PLACE.

HOOK FOR HATS, &c.

SPECIFICATION forming part of Letters Patent No. 282,023, dated July 24, 1883.

Application filed May 31, 1883. (No model.)

To all whom it may concern:

Be it known that I, FRANKLIN YOUNG, a citizen of the United States, residing at Palmer, in the county of Hampden and State of Massachusetts, have invented certain new and useful Improvements in Hanging-Hooks for Hats and Coats, and for Similar Purposes; and I declare the following to be a description of my said invention sufficiently full, clear, and exact to enable others skilled in the art to which it appertains to make and use the same, reference being had to the accompanying drawings, which form a part of this specification.

15 The object of my present invention is to provide a hanging-hook formed of wire that shall be cheap, serviceable, and convenient for hanging hats and coats, and for similar purposes; and my invention consists in an im-
20 proved wire hanging-hook, the peculiar con-
struction and nature of which are illustrated in the drawings and hereinafter more fully explained.

In the drawings, Figure 1 is a perspective view of a wire hook constructed in accordance with my invention. Fig. 2 is a front view of the same. Fig. 3 is a side view of the same. Fig. 4 is a top view of the same; and Fig. 5 is a perspective view, showing modifications in
30 the construction.

In the references, *a* and *a'* indicate the ends of the wire by which the hook is secured to the wall or strip on which it is supported. Said ends are formed into round eyes for
35 screws, or otherwise adapted for securing to the wall or wood hanging strip. From the lower end, *a'*, the wire projects forward with an upward curve, *b*. Its forward extremity is bent in the manner indicated at *c*, to pro-
40 duce lateral projections toward the right and left, which together form a broad supporting-
head or cross-bar, *C*, from which the wire is
returned along and above the part *b* for a suit-
45 able distance, and then extended upward,
making the depression or hollow bend *d*, from
the inner side of which the wire is carried
upward, as at *e*, and the upper part is pro-
vided with an overhanging loop, hook, or dou-
50 ble bend, *F*, located in relation to the head *C*
substantially as shown, and from which loop
the wire extends backward in a straight or

curved line, *g*, to the fastening end *a*, the sev-
eral parts, curves, and bends being relatively
proportioned and disposed so as to produce a
complete hanging-hook, substantially in the 55
shape indicated.

In the use of the hook the part *C* serves as
a hanging-pin or support for a hat within the
crown, while the overhanging part *F* locks
over the edge of the hat-brim and retains the 60
hat from slipping from the support *C*. The
lateral width given the part *C* serves to pre-
vent the hat from swinging around to one side,
while it gives sufficient surface to prevent the
end of the hook from straining or puncturing 65
thin fabrics that may be hung thereon. The
hollow or bend *d* accommodates the loop of a
coat or other garment. The ends *a'* are pro-
vided with eyes to receive the attaching-screws
70 *h*; or, if preferred, the ends could be made,
as indicated in Fig. 5, to be driven into the
wood, and the sides of the driven portion
could be roughened or notched, as indicated
at *a'*, to give a firm hold on the wood fibers.

Fig. 5 shows a modified form of the hook, 75
in which the upper bend, *F*, is formed double,
or with two overhanging loops located at a
short distance apart laterally, and with a pro-
jecting loop, *m*, located somewhat lower down,
thus adapting the hook for hat-brims of dif- 80
ferent widths, the wide brims to catch under
the upper bends, *F*, and narrow brims under
the lower bend, *m*.

If desired, the neck of the hook can be linked
together or twisted, as at *t*; or, if preferred, it 85
can be made without the twist. Any suitable
size of wire can be used for the construction
of the hooks, and the size of hook can be pro-
portioned to the service for which it is de-
signed.

What I claim as of my invention, and desire
to secure by Letters Patent, is—

1. A hanging-hook constructed of wire and
formed, substantially as shown, with the lat-
erally-extended head *C*, the hollow curve *d*, 95
and the overhanging curve or loop *F*, and hav-
ing ends *a'*, adapted for securing to a wall,
as set forth.

2. A hanging-hook constructed of wire, pro-
vided with a forwardly-extended portion for 100
supporting a hat within its crown, and having
at its upper part one or more overhanging

bends or loops for engaging the upper edge of the hat-brim, substantially in the manner hereinbefore described.

3. A hanging-hook constructed of wire bent into the form indicated at *b C d e F g*, with its ends *a a'* adapted for securing to a wall or other support, and having the wires at its neck *t* linked or twisted together, substantially as shown and described.

Witness my hand this 25th day of May, A. 10
D. 1883.

FRANKLIN YOUNG.
